Robert E. Smith, New York, N. Y., assignor to American Type Founders, Incorporated, Elizabeth, N. J., a corporation of New Jersey

Application March 20, 1942, Serial No. 106,261

Term of patent 14 years

To all whom it may concern:

Be it known that I, Robert E. Smith, a citizen of the United States and resident of the city, county, and State of New York, have invented a new, original, and ornamental Design for a Font of Type, of which the following is a specification, reference being had to the accompanying drawing, forming part thereof.

The drawing is a face view of a font of type showing my design.

I claim:

The ornamental design for a font of type,
as shown.

ROBERT E. SMITH.
